UNITED STATES PATENT OFFICE.

FREDERICK H. VON KELLER, OF NEW YORK, N. Y., ASSIGNEE, BY MESNE ASSIGNMENTS, TO COOPER HEWITT ELECTRIC COMPANY, OF HOBOKEN, NEW JERSEY, A CORPORATION OF NEW JERSEY.

APPARATUS FOR OPERATING MERCURY-VAPOUR LAMPS.

1,070,345.

Specification of Letters Patent. Patented Aug. 12, 1913.

Application filed August 6, 1908, Serial No. 447,218. Renewed January 27, 1913. Serial No. 744,593.

To all whom it may concern:

Be it known that I, FREDERICK H. VON KELLER, a citizen of the United States, and resident of New York, county of New York, 5 State of New York, have invented certain new and useful Improvements in Apparatus for Operating Mercury-Vapor Lamps, of which the following is a specification.

My invention relates to starting switches, 10 more especially to switches adapted to produce momentarily high voltage impulses. Switches of this character are useful, for example, in connection with vapor devices such as mercury vapor lamps described in 15 certain patents issued to Peter Cooper Hewitt on September 17th, 1901. By reason of the tendency of such lamps to go out when cold or by reason of the necessities which arise in connection with the operation 20 of such lamps when operating on low current from any cause whatsoever, a switch adapted to furnish an impulse of high potential is a very desirable auxiliary. The name "shifter" has been given to this particular type of switch and my improved shifter is illustrated in the drawings hereto annexed, in which—

Figures 1 and 2 show respectively a side elevation and an end elevation of my im- 30 proved device.

This shifter includes two bulbular portions, 1, having trunnions, 2, upon which the shifter is so mounted as to be readily rotated, and also two electrodes, 3, which 35 are often preferably of mercury and a tubular portion, 4, connecting the two bulbs 1 and partially filled with mercury. This shifter is hermetically sealed and highly exhausted. When placed in the position shown 40 in Fig. 2, the electrodes, which may be taken as of mercury for the purpose of illustration, are directly connected through the portion 4 which also will then be filled with mercury. If, however, the shifter be rotated upon the trunnions 2, a break in the 45 continuity of the mercury circuit will be introduced at two points in the neighborhood of the electrodes 3, between these elec-

trodes and the mercury in the portion 4. If such breaks occur when the device is carrying an unstable current, for example, on account of low temperature, or of small current or other condition, there will be energetic and frequently repeated attempts on the part of the negative electrode starting 55 reluctances of the negative electrodes therein to interrupt the flow of current. This action may be very active in each of the negative electrodes and the effect of the two simultaneously will be still more effective. 60 If the current here assumed as passing through the shifter, pass also through an inductance in its path, any of these energetic actions on the part of the negative electrode will cause a corresponding rise of potential 65 from the inductance which may be utilized in starting, as will hereinafter be described. Attention is called to the fact that the double shifter here shown is in some cases more effective than the single shifter and 70 proves itself a very useful device. Current is led into and out of the shifter through the sealing wires or leads, 5, which may be of platinum.

I claim as my invention:

1. A mercury vapor apparatus comprising two similar bulbous portions, having trunnions extending therefrom and having mercury electrodes and suitable lead wires therein, and a tubular passage connecting 80 the said portions and containing mercury, the said connecting portion being a mercury trap whereby the said portions are permanently separated.

2. A circuit opening device, comprising 85 an exhausted container and suitable electrodes therefor, said container being movably mounted and including the two bulbous portions connected by a U shaped tube.

Signed at New York, in the county of 90 New York, and State of New York, this 4th day of August A. D. 1908.

FREDERICK H. VON KELLER.
